RHEOSTAT

Carl R. Schenk, Millington, N. J., assignor to The
Singer Manufacturing Company, Elizabeth,
N. J., a corporation of New Jersey

Application August 13, 1935, Serial No. 35,913

5 Claims. (Cl. 201—51)

This invention relates to electric rheostats, more particularly of the carbon compression type commonly used to control the starting, stopping and speed of household sewing machine motors.

5 The invention has for an object to provide a carbon compression rheostat, the control mechanism of which offers a practically uniform mechanical resistance to displacement by the operator over the major portion of its range of motion. 10 Another object of the invention is to simplify the control mechanism and adapt it for mounting in a casing of molded phenolic condensation material which thoroughly insulates the rheostat and eliminates all danger of electric shock to the operator.

15 With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

20 In the accompanying drawings, Fig. 1 is a longitudinal vertical section through a rheostat embodying the invention. Fig. 2 is a top plan view of the rheostat. Fig. 3 is a section on the line 3—3, Fig. 2. Fig. 4 is a section on the line 25 4—4, Fig. 2. Fig. 5 is a plan view of the base member of the rheostat casing with the rheostat unit and its operating mechanism mounted thereon. Fig. 6 is a fragmentary bottom plan view of the rheostat. Fig. 7 is a fragmentary bottom plan view of the cover member of the rheostat casing. Fig. 8 is a section on the line 30 8—8, Fig. 2. Fig. 9 is a perspective view of one of the feet of the rheostat. Fig. 10 is a perspective view of the fulcrum support and recovery spring 35 anchorage horns of the rheostat operating lever. Fig. 11 is a section on the line 11—11, Fig. 7. Fig. 12 is a perspective view of the pedal slide-block.

40 Fig. 13 is a longitudinal vertical section through a modified form of rheostat adapted for mounting on the frame of a sewing machine treadle-stand and for connection by a pull-rod to the treadle of such stand. Fig. 14 is a front elevation of the rheostat with the cover broken away to show the operating mechanism. Fig. 15 is a section on the line 15—15, Fig. 13. Fig. 16 is a lower end elevation of the rheostat as shown in Fig. 14. Fig. 17 is a longitudinal section of the operating pull-block of the rheostat shown in 45 Figs. 13 and 14. Fig. 18 is an end elevation of

the pull-block, and Fig. 19 is a section on the line 19—19, Fig. 13.

5 Referring to the rheostat shown in Figs. 1 to 12, inclusive, which is adapted for operation on the floor, the casing comprises a hollow top or cover member A and a bottom or base member B, each of which is preferably molded in one piece from phenolic condensation material or artificial resin, such as "bakelite", which does not soften under heat conditions and has good 10 mechanical strength and high electrical insulating properties. The top member A is preferably of hollow rectangular form and comprises a top wall 1 and side walls 2 which latter are formed with internal corner ledges 3. The bottom member 15 B is substantially flat and preferably of rectangular form and is detachably secured to the top member A, within the side walls 2 of the latter, by means of the corner screws 4 which are screwed into the ledges 3. The bottom member 20 B has rounded corners 5 which are spaced from the rounded internal corner walls 6 of the top member A to form pockets to receive and position the vertical shank 1 of the rubber feet C. The shanks 7 of the feet C have flanges 8 at 25 their upper ends overlapping the bottom member B and these flanges are clamped by and between the bottom member B and the ledges 3 of the top member A. The feet C may have at their lower ends the tread portions 9 which may 30 be of annular form and which may underlap the bottom member B.

35 Mounted on the base member B by means of screws 10 is the usual carbon compression type rheostat unit 11, such as disclosed in the U. S. Patent to Chason, No. 1,643,292; dated Sept. 27, 1927. Such a rheostat unit comprises a porcelain body having spaced parallel wells housing stacks 12 of carbon disks, which stacks are each connected at one end to a terminal screw 13 40 and at its opposite end to a conducting pressure head 14. The pressure heads 14 are bridged by a weak bow-spring 15 carried by the operating pull-rod 16 which also carries the stiffer backing spring 17. The pull-rod 16 is surrounded by the 45 coiled recovery spring 18 which tends to return the pull-rod 16 to the "off" position shown in Fig. 5 in which the weak bow-spring 15 is out of engagement with the pressure heads 14 and the circuit through the rheostat is broken. A 50 pull on the rod 16 first closes the circuit through the rheostat and applies an increasing weak pressure to the stacks 12 of carbon disks which gradually lowers their electrical resistance. Because 55 of the non-rectilinear characteristic curve of a

carbon compression resistor it is desirable in the later stages of movement of the pull-rod 16 to apply greater pressures to the carbon disks than would be possible by the action of the weak 5 bow-spring 15 alone and this is accomplished by the action of the stiffer backing spring 17. Hence the operative pull upon the rod 16 must increase more rapidly than the distance travelled by the rod 16 in order to overcome the cumulative 10 mechanical resistances offered by the springs 18, 15 and 17.

The pull-rod 16 has screwed onto its free end the adjusting nut 16' which is engaged by the strap 19 pivotally connected at 20 to the lever 21 15 fulcrumed at 22 on the ears 23 of the plate 24 screwed to the base B. The lever 21 has an operating arm 25 which carries a cross-bar 26 to the ends of which are connected the tensioned recovery springs 27 anchored to the notched horns 28 20 rising from the plate 24 at opposite sides of the pull-rod 16, nut 18 and pull-strap or stirrup 19. The springs 27 are adjustable along the horns 28 and may each be shifted to any one of the plurality of notches 28' in its respective horn 28.

25 It will be observed in Fig. 1 that the recovery springs 27, which are comparatively strong, extend transversely of the pivotal axis 22 of the lever 21 and that the longitudinal axes of the springs 27 are spaced above the pivotal axis 22 30 of said lever. Hence, a down push on the cross-bar 26 carries the springs 27 downwardly toward the pivotal axis of the lever 22 and the closer such pivotal axis is approached, the less is the recovery effect of the springs 27 on such lever. 35 The weakening effect of the recovery springs 27 on the lever 21 more or less balances the cumulative mechanical resistance of the springs 18, 15 and 17, so that substantially uniform pressure upon the cross-bar 26 will move the latter 40 through the major portion of its range of motion.

The cover A is formed with a rectangular vertical guideway 29, Fig. 7, in which is fitted the pedal slide 30 slotted or bifurcated at 31 to straddle the lever 21 and having at its lower end the faces 32 resting on the cross-bar 26. Stop lugs 33 45 on the pedal 30 prevent upward withdrawal of the latter from the guideway. A guide arm 34, Fig. 11, steadies the pedal 30 in the guideway 29.

It will be observed in Figs. 1 and 3 that ventilating space is provided between the edges of the base B and the side walls of the cover A, which latter has ventilating slots 35 in its top 1.

One of the side walls 2 of the cover A is formed with a conductor-cord receiving slot 36, Fig. 7, 55 having a toothed or roughened top wall 37 against which the conductor cord 38 is gripped by the toothed upper face 39 of the tongue 40 on the base B. The cover A is also provided with the foot rest 41 to better enable the operator to control the movement of the pedal 30.

In the modification of the invention shown in Figs. 13 to 19, inclusive, the rheostat is not to be operated by a pedal but is adapted to be mounted in a substantially vertical position, as shown in 65 Fig. 14, on the frame of a sewing machine treadle-stand and operated by a straight pull connection to the treadle member of the stand. In this modification, the casing comprises a base D and removable hollow cover E housing a carbon compression resistor unit 11 identical with that shown in the preceding figures. The pull-rod 16 of this rheostat, adjusting nut 16' and pull-strap 19 are identical with the like parts of the preceding figures, as are the lever 21, cross-bar 26, fulcrum- 70 plate 24 and horns 28, for the recovery springs 27.

The difference in the two constructions resides mainly in the substitution for the push-pedal 30 of a pull-block 42 molded from phenolic condensation material with the slotted metal insert pull-plate 43. The pull-block 42 is connected to the long screw 44 which replaces the short screw 20 of Figs. 1 and 2. The block 42 is slotted in its under side at 45, Fig. 17, to straddle the lever 21. It is also formed with notches 46 to clear the cross-bar 26. The pull-block 42 is guided by the 10 guideway 47 in the casing. A stop lug 48 on the block 42 arrests the down movement of the latter.

The invention is not to be understood as limited to details of construction and relative arrangements of parts not particularly specified in the 15 appended claims.

Having thus set forth the nature of the invention, what I claim herein is:—

1. The combination with a carbon compression rheostat including a carbon compression resistor, 20 an operating pull-rod, and spring means controlled by said rod to apply operative pressures to said resistor, a casing for said resistor, a lever fulcrumed in said casing and connected to said pull-rod, said lever having an operating arm, a 25 pedal arranged to depress said arm, and a tension-spring having its longitudinal axis spaced above and extending transversely of the pivotal axis of said lever, said spring being connected at one end to said operating arm and anchored at 30 its other end to said casing, the space between the longitudinal axis of said spring and the pivotal axis of said lever decreasing in the electrical resistance decreasing motion of said lever, and means to vary the initial spacing of the longitudinal axis of said spring above the pivotal axis 35 of said lever.

2. The combination with a carbon compression rheostat including a carbon compression resistor, an operating pull-rod, and spring means 40 controlled by said rod to apply operative pressures to said resistor, a casing for said resistor, a lever fulcrumed in said casing and connected to said pull-rod, said lever having an operating arm, a pedal arranged to depress said arm, and a tension-spring having its longitudinal axis spaced 45 above and extending transversely of the pivotal axis of said lever, said spring being connected at one end to said operating arm, a spring-anchor- 50 age arm fixed within said casing, the other end of said spring being connected to and shiftable longitudinally of said spring-anchorage arm to vary the spacing between the longitudinal axis of said spring and the pivotal axis of said lever.

3. A rheostat comprising a hollow casing including a top member of molded phenolic condensation material formed with a guideway, a bottom member, a manually operated member of molded phenolic condensation material slidably fitting said guideway and having a bifurcated end 60 within said casing, a lever fulcrumed on said bottom member within said casing and straddled by said manually operated member, a recovery spring connected to said lever, and a carbon compression resistor unit mounted within said casing 65 and having an operating pull-rod connected to said lever.

4. A rheostat comprising a hollow casing including separable cover and base members, a carbon compression resistance unit mounted within 70 said casing and having an operating pull-rod, an adjusting nut screw-threaded onto said pull-rod, a strap engaging said adjusting nut, a lever fulcrumed on said base and connected to said strap, a cross-bar on said lever, a U-shaped spring an- 75

5. chorage fixed to said base and including spaced horns extending away from said base at opposite sides of said pull-rod, nut and strap, a pair of tension-springs each connecting an end of said cross-bar with a respective one of said spaced horns, and manually controlled means to operate said connected lever, strap, nut and pull-rod.

5. The combination with a carbon compression rheostat including a carbon compression resistor, an operating pull-rod, and a spring system controlled by said rod to apply operative pressures to said resistor, a casing for said resistor, a lever fulcrumed in said casing and connected to said pull-rod, said lever having an operating arm, a

pedal arranged to depress said arm, and a compensating recovery spring system including a tension-spring connected at one end to said operating arm and anchored at its other end to said casing, said tension-spring having its longitudinal axis initially spaced above and extending across the vertical plane of the pivotal axis of said lever in the "off-position" of said pedal, the space between the longitudinal axis of said spring and the pivotal axis of said lever decreasing throughout the electrical resistance decreasing motion of said pedal. 5
